UNITED STATES PATENT OFFICE.

ISRAEL JOUBERT AND SYDNEY W. YATTAW, OF PORT HENRY, NEW YORK.-

BUCKBOARD-WAGON.

SPECIFICATION forming part of Letters Patent No. 254,332, dated February 28, 1882.

Application filed August 6, 1881. (No model.)

To all whom it may concern:

Be it known that we, ISRAEL JOUBERT and SYDNEY W. YATTAW, of Port Henry, in the county of Essex and State of New York, have 5 invented a new and useful Improvement in Buckboard-Wagons; and we do hereby declare that the following is a full, clear, and exact description of the same, reference being had to the accompanying drawings, forming part of 10 this specification, in which—

Figure 1 is a perspective view of our improved buckboard and stiffening-frame, and Fig. 2 is a side elevation of the same with a wagon-body secured thereto.

15 Our invention relates to improvements in buckboard-wagons; and it consists of a wagon-buckboard provided with a stiffening-frame secured to the middle of the buckboard and adapted to support a wagon-body, and having 20 its slats concaved or curved in an opposite or reverse direction to the slats of the buckboard, as hereinafter more fully set forth.

In the accompanying drawings, *a* represents 25 a buckboard of the usual construction composed of a series of longitudinal, parallel, and upwardly-curved wooden spring-slats, *b*, having interstices or openings between them and secured to transverse end bars, *c c*, and middle cross-bar, *d*. The transverse end bars, *c c*, are 30 adapted to be secured to the fore and hind axles of a wagon, and the buckboard thus serves as a reach for connecting the axles, and as a wagon-spring, in the usual manner.

h represents our improved stiffening-frame, 35 composed of a series of longitudinal parallel wooden spring-slats, *k*, curved downwardly or

in an opposite direction to the curved spring-slats *b* of the buckboard, and secured at their ends to the transverse bars *l*, to which the bottom of a wagon-body is secured. The downwardly-curved spring-slats *k* are inserted in 40 the interstices between the upwardly-curved spring-slats *b*, and are secured at their middles to the under face of the middle transverse bar, *d*, of the buckboard to hold the stiffening-frame in 45 position on the buckboard, with the cross-bars *l l* of the stiffening-frame resting on the slats of the buckboard.

Any weight applied to the wagon-body will cause the curve of the buckboard to flatten and 50 the wheels of the wagon and axles to be moved apart, and the transverse bars of the stiffening-frame to slide along the slats of the buckboard. The construction materially strengthens and 55 stiffens the spring of the buckboard and renders it more durable, and the wagon-body can be elevated as desired by shortening the stiffening-frame.

We claim as our invention—

The combination, with a wagon-buckboard, 60 *a*, of the stiffening-frame *h*, having the parallel downwardly-curved slats *k* inserted in the openings between the slats of the buckboard, and secured thereto, and provided with the end transverse bars, *l*, adapted to support a wagon-body, substantially as described, and for the 65 purpose set forth.

ISRAEL JOUBERT.

SYDNEY WESTREN YATTAW.
